UNITED STATES PATENT OFFICE.

JOSEPH CHYTRACEK, OF CLIFTON MILLS, WEST VIRGINIA.

ASH-SIFTER.

1,354,243.

Specification of Letters Patent. Patented Sept. 28, 1920.

Application filed June 4, 1920. Serial No. 386,525.

To all whom it may concern:

Be it known that I, JOSEPH CHYTRACEK, a citizen of the United States of America, residing at Clifton Mills, in the county of 5 Preston and State of West Virginia, have invented certain new and useful Improvements in Ash-Sifters, of which the following as a specification.

The present invention relates to certain 10 new and useful improvements in ash sifters and particularly to that type embodying a revoluble screen drum or cylinder positioned within a casing and adapted to be rotated by an operating crank. 15 A further object of the invention resides in the provision of an ash sifter embodying a rotatable sifting drum arranged within a casing and adapted for automatic projection from the casing when the casing lid is 20 opened, and a controlling device is shifted to the required position.

With the above general objects in view and others that will appear as the nature of the invention is better understood, the same 25 consists in the novel form, combination and arrangement of parts hereinafter more fully described, shown in the accompanying drawings and claimed.

In the drawings, wherein like reference 30 characters designate corresponding parts throughout the several views,

Figure 1 is a longitudinal sectional view of an ash sifter constructed in accordance with the present invention,

Fig. 2 is a vertical transverse sectional view on line II—II of Fig. 1 showing the sifting drum supporting frame shifted in its dotted line position with the sifting drum projecting from the casing in dotted line 40 position,

Fig. 3 is a cross sectional view of the sifting drum removed from the casing and supporting frame,

Fig. 4 is a fragmentary sectional view 45 showing the manner of attaching the operating crank to the screen cylinder, and

Fig. 5 is a fragmentary perspective view of the sifting drum supporting frame.

Referring more in detail to the accompanying drawings, there is illustrated an ash sifter formed of a casing including an inclined bottom wall 6, side walls 7 and a front top wall or cover 8 while a vertical sliding gate 9 controls the entries to the forward end of the casing. As shown in Figs. 1 and 2, the rear ends 7' of the side walls 7

extend upwardly above the front cover wall 8 and are substantially circular at their upper ends and carry inwardly directed flanges 10 while a curved cover 11 is hinged at its rear edge as at 12 to the rear wall 13 of the casing while the forward edge thereof is suitably secured as by the clip 14 to the front cover wall 8.

A screen supporting frame is pivotally mounted within the casing and embodies a cross bar 15 positioned outwardly of the casing and above the cover 11 thereof while an operating handle 16 is centrally carried thereby. As shown in Fig. 1, legs 17 and 18 are carried by the opposite ends of the cross bar 15 and freely extend through slots 19 provided in the flanges 10 of the end wall extensions 7' with the inner ends thereof rotatably supported upon the end walls 7', 75 the legs 17 carrying an apertured boss 20 received on the pin 21 carried by the wall 7' while the leg 18 carries an outwardly directed annular flange 22 rotatably supported upon the inwardly directed boss 23 80 carried by the adjacent end wall 7', this construction being more clearly shown in Figs. 1 and 4. In this manner, the sifting drum supporting frame is rotatably mounted within the casing upon the axially alined pin 85 21 for the arm 17 and the tubular boss 23 for the leg 18. Extensions 24 and 25, each slotted as at 26 are carried by the legs 17 and 18 respectively, and extend therefrom at obtuse angles as shown in Figs. 2 and 5 90 to provide slidable bearings for the ends of the sifting drum.

The sifting drum is of the form best illustrated in Figs. 1 and 3 as embodying end disks 27 carrying axial pins 28 and 29 upon 95 which blocks 30 are journaled, the blocks 30 being positioned between the legs 17 and 18 with the outer ends of the pins 28 and 29 projecting into the slots 26 of the leg extensions 24 and 25 to form bearings for the 100 cylinder disks. A screen section 31 is fixed at its ends to the disks 27, and the screen section 32 is hinged to the disks as at 33 at one side thereof, while the opposite side of the screen section 32 is provided with a clip 105 34 for securing the screen section in position. With the sifting drum supporting frame in the full line position shown in Fig. 2, the leg extensions 24 and 25 are declined as illustrated and the bearing pins 28 and 29 are retained in the ends of the slots 26 110 adjacent the bearings 30 by the springs 35

secured at one end as at 36 to the flanges 10 and at the other ends as at 37 to the blocks 30.

A crank 38 is adapted to be projected through the tubular boss 23 for engagement 5 with the crank end 39 of the bearing pin 29, and by rotation of the crank 38 the pin 29 being fixed to the adjacent disk 27 will rotate the sifting drum upon the pins 28 and 29 with the blocks 30 remaining stationary, 10 and with the ends of the slots 26 adjacent the bearings 20 and 23 forming the journal bearings for said pins. In order to introduce ashes or other material into the screen to be sifted, the cover 11 is opened 15 to the dotted line position shown in Fig. 2 and the handle 16 of the screen supporting frame moved downwardly adjacent the front cover wall 8 to vertically position the slotted leg extensions 24 and 25, at which 20 time the springs 35 will elevate the blocks 30 and the bearing pins in the extension slots 26 to project the sifting drum through the opening created by the opening of the cover 11. When so arranged, the screen section 32 may be opened and the material introduced into the sifting drum. In a reverse manner, the sifting drum is lowered 25 into the casing, by pressing downwardly upon the same and thereafter shifting the handle frame 15 to cause the slotted leg extensions 24 and 25 to be downwardly directed as shown in Fig. 2. Again, when in 30 this position, the application of the crank 38 to the bearing pin 29 will effect rotation 35 of the sifting drum within the casing and the finer particles delivered upon the bottom wall 6 may be removed by elevating the front gate 9.

While there is herein shown and described 40 the preferred embodiments of the present invention, it is nevertheless to be understood that minor changes may be made therein without departing from the spirit and scope of the invention as claimed.

45 What is claimed as new is:—

1. An ash sifter of the type described comprising a casing, a sifting drum revolvably mounted within the casing, and movable means for supporting the drum adapt-

ed upon shifting movement thereof automatically to project the drum from the casing.

2. An ash sifter of the type described comprising a casing, a sifting drum revolvably mounted within the casing, and movable means for supporting the drum adapted upon shifting movement thereof automatically to project the drum from the casing, said movable means including a frame having slotted leg extensions in which the drum 55 is revolvably mounted.

3. An ash sifter of the type described comprising a casing, a sifting drum revolvably mounted within the casing, movable means for supporting the drum adapted 60 upon shifting movement thereof automatically to project the drum from the casing, said movable means including a frame having slotted leg extensions in which the drum 65 is revolvably mounted, and springs arranged 70 between the casing and drum for moving the drum in said slots.

4. An ash sifter of the type described comprising a casing, a sifting drum revolvably mounted within the casing, and movable means for supporting the drum adapted 75 upon shifting movement thereof automatically to project the drum from the casing, said means including a frame having slotted leg extensions in which the drum 80 is rotatably mounted and normally positioned with the outer ends of the slots declined.

5. An ash sifter of the type described comprising a casing, a sifting drum revolvably mounted within the casing, movable means for supporting the drum adapted 85 upon shifting movement thereof automatically to project the drum from the casing, said means including a frame having slotted leg extensions in which the drum 90 is rotatably mounted and normally positioned with the outer ends of the slots declined, and means for holding the rotatable drum in the upper ends of the slots when the drum 95 is positioned within the casing.

In testimony whereof I affix my signature.

JOSEPH CHYTRACEK.
